UNITED STATES PATENT OFFICE.

GEORGE F. READ, OF NEW YORK, N. Y., ASSIGNOR TO ROBERT HOE, OF NEW YORK, N. Y.

PNEUMATIC SHEET-CARRYING DEVICE.

SPECIFICATION forming part of Letters Patent No. 700,289, dated May 20, 1902.

Application filed July 29, 1901. Serial No. 70,077. (No model.)

To all whom it may concern:

Be it known that I, GEORGE F. READ, a citizen of the United States, residing at New York, county of Kings, and State of New York, have 5 invented certain new and useful Improvements in Pneumatic Sheet-Carrying Devices, fully described and represented in the following specification and the accompanying drawings, forming a part of the same.

10 This invention relates to certain improvements in pneumatic sheet-carrying devices for use in printing and other analogous machines.

Heretofore the pneumatic sheet-carrying 15 devices of printing-machines as usually constructed have consisted of a cylinder provided with air-channels, which underlie perforated sections in the periphery of the cylinder, said air-channels communicating by suitable pipes 20 with the shaft of the cylinder, which was perforated or made hollow. This perforated shaft was connected with a suction-producing mechanism, the communication between the suction mechanism and the air-channels being 25 usually controlled by means of valves, the entire construction being complicated and requiring special mechanism for operating the valves.

One of the objects of the present invention 30 is to produce a simple and cheap pneumatic sheet-carrier in which the use of a hollow or perforated shaft is unnecessary.

A further object of the invention is to produce 35 a pneumatic sheet-carrier in which the valves heretofore employed and the mechanism for operating them are rendered unnecessary.

A further object of the invention is to produce 40 an improved pneumatic sheet-carrier from which the sheet is delivered with certainty and accuracy at the delivery-point.

With these and other objects in view the invention consists in certain constructions and in certain parts, improvements, and combinations, as will be hereinafter fully described and then specifically pointed out in 45 the claims hereunto appended.

In the accompanying drawings, in which like characters of reference indicate the same parts, Figure 1 is a side elevation of the delivery portion of a printing-machine provided 50 with the improved sheet-carrier. Fig. 2 is a

detail front elevation, partly in section, of the sheet-carrying cylinder on an enlarged scale. Fig. 3 is an enlarged sectional end view of the sheet-carrier and certain of the mechanism 55 coöperating therewith, the plane of section being indicated by the line 3 3 in Fig. 2. Fig. 4 is a sectional view on the line 4 4 of Fig. 2.

Referring to the drawings, which illustrate one embodiment of the invention, 1 indicates 60 the frame of the machine, which may be of any suitable construction. Mounted in suitable bearings in the frame are cutting-cylinders 2 and 3, the cylinder 2 being provided with the usual cutting-blades 4 and the cylinder 65 3 being provided with the coöperating cutting-blocks 5. In the construction shown the cylinder 3 is provided with suction sheet-holding devices, so that it may carry the sheets 70 onward after they are cut.

The suction devices on the cylinder may be varied widely in construction. As shown, however, the cylinder is provided with a plurality of suction-channels 6, which may be integral with the cylinder, as shown, or may 75 be separate therefrom and secured thereto in any suitable manner. The outer walls of these channels are in the construction shown formed by the cutting-blocks 5, said blocks being provided with suitable perforations 7, 80 through which the suction acts. In the preferred form of the construction these channels 6 will be located near the periphery of the cylinder, although they might be otherwise located, if desired.

The means by which suction is created in the channels 6 may be varied within wide limits. As shown, there is provided a head or casting 8, which may be mounted or supported in any suitable manner. This casting 90 is provided with a hub 9, through which the shaft 10 of the cylinder passes loosely, so that the head is supported by the shaft. The head 8 is stationary with respect to the shaft and the cylinder, and means which may be 95 of any suitable construction are preferably provided for insuring that the head will be held stationary. As shown, the bearing of the shaft 10 is provided with ears 11, through which pass screws 12, said screws entering 100 the head and locking it against movement.

The head 8 is provided with an air-cham-

ber, which may be of any suitable configuration. As shown, this air-chamber, which is marked 13, is circular in form, its outer wall being formed by a flange 14, which forms the 5 periphery of the head, and its inner wall being formed by a flange 15, which projects inwardly from the head. This air-chamber lies along the line of movement of the channels 6, and these channels are therefore in open communication with the chamber as the cylinder 10 rotates.

The air may be exhausted from the chamber 13 in any desired manner. As shown, however, the chamber is provided with a suitable opening which communicates with a pipe 16, leading to any suitable form of suction-producing device—as, for instance, a fan, the casing of which is indicated at 17 in Fig. 1. As shown, the fan is driven by means of 20 a belt 18 and pulley 19, said belt running over another pulley 20, mounted on a shaft 21, which is driven from any suitable source of power. The suction-producing fan operates continuously to draw the air from the 25 chamber 13. Inasmuch as the suction-channels 6 are in open communication with the chamber, except as hereinafter specified, it will be seen that in the rotation of the cylinder as soon as one of the cutting-blocks 5 30 comes in contact with a web of paper the web will be clamped against the block by the force of the suction and will be held against the cylinder until the suction is cut off by means now to be described.

35 The means by which the suction is cut off from the channels in order to release the sheet may be varied within wide limits. Preferably, however, these means will be carried by the head, before referred to, and will be adjustable with relation to it, so that the suction may be cut off at any desired point. When, as in the preferred form of the construction, the air-chamber is circular in configuration, the means for cutting off the suction from the channels will preferably consist of an arc-shaped block 22, which is located in the chamber, said block corresponding in size to the cross-sectional area of the chamber, so that it entirely fills it. As the cylinder 40 rotates, therefore, it will be seen that as the mouth of each channel 6 comes opposite the block the suction will be cut off from the channel and will remain cut off until the mouth of the channel has passed the block. The 45 block 22 is preferably made adjustable, so that the suction may be cut off at any desired point in the rotation of the cylinder, the means by which the adjustment is effected being of any desired construction. As shown, the 50 head is provided with a slot 23, and the block 22 carries a pin 24, (see Fig. 2 and dotted lines in Fig. 3,) the head of this pin being provided with a suitable nut 25. By loosening the nut the block may be adjusted to any 55 desired position in the channel within the limits of the length of the slot. The block is preferably so located in the head that it will

operate to cut off the suction from the channels just before the channels reach the sheet-delivery point, so that the sheets may be 70 dropped easily into the sheet-receiver and without being thrown against the side of the receiver with undue force. The position of the block may therefore be varied according to the speed at which the carrier is run and 75 according to the weight of the paper.

Any suitable form of sheet-receiving device may be employed. As shown, the sheet-receiver consists of a table 26, mounted on a bracket 27, secured to a suitable slide 28, 80 which moves in vertical guides 29. The slide 28 is connected by means of a cable 30 to a balance-spring 31, so that the weight of the sheets deposited on the receiver may cause it to move downward. This receiver is a well-known one, and any other suitable form of receiver may be substituted therefor.

In order to insure the positive separation of the forward end of the sheet from the cylinder after the suction has been cut off, a suitable stripper is preferably provided. This stripper may be of any suitable construction. As shown, the shaft 32 is provided suitably mounted in the frame of the machine, said shaft being provided with stripper-fingers 33, 95 which enter grooves 34 in the cylinder, the stripper being so located as to catch the forward edge of the sheet as soon as the suction is cut off.

It has been found by practical experience 100 that when the carrier is run at a high rate of speed the sheets are apt to adhere to the surface of the cylinder, even though a stripper be employed. To prevent the sheets from adhering to the cylinder, suitable means are 105 or may be provided which act upon the sheet between its ends and force it from the cylinder. In the construction shown the cylinder is slotted, as indicated at 35, between each of the suction-channels. Through these slots 110 work fingers 36, which are carried on shafts 37, suitably mounted in ears 38 on the interior of the cylinder. Each of the shafts 37 is provided with an arm 39, which carries a bowl 40, arranged to contact with a stationary 115 cam 41, connected to the hub 9 of the head 8. The cam is so located as to rock the shaft to throw out the fingers at about the time when the stripper catches the forward edge of the sheet. The fingers 36 may be returned 120 to their position within the cylinder in any desired manner. As shown, each of the shafts 37 is provided with an arm 42, which is connected to an ordinary spring-rod 43.

The web is indicated at W, and after passing 125 over two guide-rolls 44 and 45, a guide 46, and between slitters 47 (all of which parts may be of any usual construction) it passes under a roll 48, which is mounted in suitable arms 49, pivoted at 50 in the frame of the machine, and is forced against the periphery of the cylinder by a spring-rod 51. As the cutting-blocks 5 successively pass beneath the roll 48 the web is forced against it by this 130

roll, and as the mouth of the suction-channel beneath each block has passed off the cutting-off block 22 at this time the suction is operating and acts to clamp the web firmly to the block 5. As the cutter 3 continues its rotation one of the blades 4 comes into action and cuts a sheet from the web, the sheet being carried onward by the carrier. In order to hold the sheet snugly against the carrier, suitable tapes 52 are provided. These tapes are mounted in any usual manner, and a description of the means by which they are mounted and the rolls on which they run is therefore regarded as unnecessary.

15 The operation of the machine will be readily understood from the foregoing description, and a detailed description thereof is therefore unnecessary.

While the invention as shown is embodied 20 in a sheet-carrier which forms one of a pair of cutting-cylinders, it is to be understood that it may be applied to cylindrical sheet-carriers other than cutting-cylinders and to sheet-carriers which are not cylindrical in 25 form and do not, therefore, move in a circular path. The invention is not, therefore, to be limited to the specific construction hereinbefore described, as it may be embodied in other forms of construction.

30 What is claimed is—

1. The combination with a moving sheet-carrier provided with a suction-channel, of a stationary part located along the line of movement of the carrier and having an air-chamber with which the channel communicates, and adjustable means for interrupting the communication between the channel and the chamber, substantially as described.

2. The combination with a moving sheet-carrier provided with a suction-channel, of a stationary part located along the line of movement of the carrier and having an air-chamber with which the suction-channel communicates, and a block located in the chamber for 45 interrupting the communication between the channel and the chamber, substantially as described.

3. The combination with a moving sheet-carrier provided with a suction-channel, of a stationary part located along the line of movement of the carrier and having an air-chamber with which the suction-channel communicates, and an adjustable block located in the chamber for interrupting the communication 55 between the channel and the chamber, substantially as described.

4. The combination with a rotating sheet-carrying cylinder provided with a suction-channel, of a stationary part having an air-chamber with which the channel is in communication as the cylinder rotates, and a block in the chamber for interrupting the communication between the chamber and the channel, substantially as described.

65 5. The combination with a rotating sheet-carrying cylinder provided with a suction-channel, of a stationary part having an air-

chamber with which the channel is in communication as the cylinder rotates, and an adjustable block in the chamber for interrupting the communication between the chamber and the channel, substantially as described.

6. The combination with a rotating sheet-carrying cylinder provided with a suction-channel, of a stationary part having a circular air-chamber with which the channel is in communication as the cylinder rotates, and means located in the chamber for interrupting the communication between the channel and the chamber, substantially as described.

7. The combination with a rotating sheet-carrying cylinder provided with a suction-channel, of a stationary part having a circular air-chamber with which the channel is in communication as the cylinder rotates, and 85 adjustable means located in the chamber for interrupting the communication between the channel and the chamber, substantially as described.

8. The combination with a rotating cylinder 90 provided with a suction-channel, of a stationary head having an air-chamber with which the channel is in communication, and adjustable means carried by the head for interrupting the communication between the channel 95 and the air-chamber, substantially as described.

9. The combination with a rotating cylinder provided with a suction-channel, of a stationary head having a circular air-chamber with 100 which the channel communicates, and means carried by the head for interrupting the communication between the channel and the air-chamber, substantially as described.

10. The combination with a rotating cylinder 105 provided with a suction-channel, of a stationary head having a circular air-chamber with which the channel communicates, and adjustable means carried by the head for interrupting the communication between the channel 110 and the air-chamber, substantially as described.

11. The combination with a rotating cylinder provided with a suction-channel, of a stationary head having a circular air-chamber 115 with which the channel communicates, and means carried by the head and located in the chamber for interrupting the communication between the channel and the air-chamber, substantially as described.

12. The combination with a rotating cylinder provided with a suction-channel, of a stationary head having a circular air-chamber, with which the channel communicates, and adjustable means carried by the head and located in the chamber for interrupting the communication between the channel and the air-chamber, substantially as described.

13. The combination with a rotating cylinder provided with a suction-channel, of a stationary head having a circular air-chamber with which the channel communicates, and an adjustable block carried by the head and located in the chamber for interrupting the

communication between the channel and the air-chamber, substantially as described.

14. The combination with a rotating cylinder having a suction-channel, of a stationary part having an air-chamber with which the channel communicates, means for interrupting the communication between the channel and chamber, and means for throwing the sheet off the cylinder when communication between the channel and the chamber has been interrupted, substantially as described.

15. The combination with a rotating cylinder having a suction-channel, of a stationary part having an air-chamber with which the channel communicates, means for interrupting the communication between the channel and chamber, and a stripper for removing the forward edge of the sheet from the cylinder when communication between the channel and the chamber has been interrupted, substantially as described.

16. The combination with a rotating cylinder having a suction-channel, of a stationary part having an air-chamber with which the channel communicates, means for interrupting the communication between the channel and chamber, and means acting upon the sheet between its ends to throw it off the cylinder when communication between the channel and the chamber has been interrupted, substantially as described.

17. The combination with a rotating cylinder having a suction-channel, of a stationary part having an air-chamber with which the channel communicates, means for interrupting the communication between the channel and chamber, and means acting upon the forward edge of the sheet and means acting upon the sheet between its ends to remove it from the cylinder when communication between the channel and the chamber has been interrupted, substantially as described.

18. The combination with a rotating cylinder having a plurality of suction-channels near its periphery, of a stationary head having an air-chamber therein with which the channels communicate, means for interrupting the communication between the channels and the air-chamber, arms carried by the cylinder and arranged to operate upon the sheet when communication between the air-chamber and suction-channels is interrupted, and a stationary cam for throwing the arms into operation, substantially as described.

19. The combination with a rotating cylinder having a suction-channel therein, of a stationary cylinder-head having an air-chamber with which the channel communicates, a block mounted in the head and arranged to close the suction-channel, and an adjusting and locking pin extending through the slot and serving to position the block, substantially as described.

20. The combination with a rotating cylinder having a plurality of suction-channels arranged near its periphery, of a head having a circular air-chamber with which the chan-

nels communicate, and an arc-shaped block located in the chamber and serving to close the channels successively as they pass it, substantially as described.

21. The combination with a rotating cylinder having a plurality of suction-channels arranged near its periphery, of a head having a circular air-chamber with which the channels communicate, an arc-shaped block located in the chamber and serving to close the channels successively as they pass it, and means for adjusting the block, substantially as described.

22. The combination with a rotating cylinder having a plurality of suction-channels arranged near its periphery, of a head having a circular air-chamber with which the channels communicate, an arc-shaped block located in the chamber and serving to close the channels successively as they pass it, and a pin-and-slot connection for adjusting the block and locking it in position, substantially as described.

23. The combination with a pair of cutting-cylinders, one of said cylinders having a plurality of suction-channels, of a stationary head provided with an air-chamber with which the channels communicate, means for interrupting the communication between the chamber and the channels, a sheet-receiver, a stripper acting upon the forward edge of the sheet, and pivoted delivery-arms, said arms and stripper operating to deliver the sheet to the sheet-receiver, substantially as described.

24. The combination with a pair of cutting-cylinders, one of which is provided with a plurality of suction-channels, of a stationary head having an air-chamber with which the channels communicate, an adjustable block located in said chamber and serving to interrupt the communication between the chamber and the channels, a sheet-receiver, a stripper acting upon the forward edge of the sheet, and pivoted delivery-arms, said arms and stripper operating to deliver the sheet to the sheet-receiver, substantially as described.

25. The combination with a pair of cutting-cylinders, one of which is provided with a plurality of suction-channels, of a stationary head having a circular air-chamber with which the channels communicate, means for interrupting the communication between the chamber and the channels, a sheet-receiver, a stripper acting upon the forward edge of the sheet, and pivoted delivery-arms, said arms and stripper operating to deliver the sheet to the sheet-receiver, substantially as described.

26. The combination with a pair of cutting-cylinders, one of which is provided with a plurality of suction-channels, of a stationary head having a circular air-chamber with which the channels communicate, adjustable means for interrupting the communication between the chamber and the channels, a sheet-receiver, a stripper acting upon the forward edge of the sheet, and pivoted delivery-

arms, said arms and stripper operating to deliver the sheet to the sheet-receiver, substantially as described.

27. The combination with a pair of cutting-cylinders, one of which is provided with a plurality of suction-channels, of a stationary head having a circular air-chamber with which the channels communicate, an adjustable block for interrupting the communication between the chamber and the channels, a sheet-receiver, a stripper acting upon the forward edge of the sheet, and pivoted delivery-arms, said arms and stripper operating to deliver the sheet to the sheet-receiver, substantially as described.

28. The combination with a pair of cutting-cylinders, one of which is provided with a

plurality of suction-channels near its periphery, of a stationary head having a circular air-chamber with which the channels communicate, an adjustable block for interrupting the communication between the chamber and the channels, a sheet-receiver, a stripper acting upon the forward edge of the sheet, and pivoted delivery-arms, said arms and stripper operating to deliver the sheet to the sheet-receiver, substantially as described.

In testimony whereof I have hereunto set my hand in the presence of two subscribing witnesses.
